UNITED STATES PATENT OFFICE.

TIMOTHY J. COLLINS, OF TOLEDO, OHIO, ASSIGNOR TO RANSOM & RANDOLPH, OF SAME PLACE.

DESIGN FOR A BARBER'S DRESSING-CASE.

SPECIFICATION forming part of Design No. 19,778, dated April 29, 1890.

Application filed April 2, 1890. Serial No. 346,342. Term of patent 3½ years.

To all whom it may concern:

Be it known that I, TIMOTHY J. COLLINS, of Toledo, in the county of Lucas and State of Ohio, have invented and produced a new and original Design for Barbers' Dressing-Cases; and I do hereby declare that the following is a full, clear, and exact description of the invention, which will enable others skilled in the art to which it appertains to make and use the same, reference being had to the accompanying photograph, and to the letters of reference marked thereon, which form part of this specification.

The photograph represents a perspective view of my newly-designed barber's dressing-case.

The leading features of my design are a dressing-table A, resting upon rectangular supports B, one in each side, which supports are closed in front by panel-doors C, which are surmounted by drawers D. The rectangular recess between the supports is closed on the rear side by the back E, and there is an ornamental connecting-piece F between the drawers D. Upon the supports B there

is mounted a frame-work G, in which there is placed a large mirror H and four small mirrors I, the latter being arranged above the former. Upon the front side of each side rail of the frame-work G there is a bracket J, on each of which is placed a small shelf k. The frame-work G is surmounted by a cap-piece L, having molding M around the under side of its overhanging edges, and on top of the cap-piece there is a carved ornament N, extending entirely across it, this ornament having a short narrow rail O connected to it by small turned pins P.

What I claim is—

The design for a barber's dressing-case having the shape and ornamentation herein shown and described.

In testimony that I claim the foregoing as my own I hereby affix my signature in presence of two witnesses.

TIMOTHY J. COLLINS.
